United States Patent Office.

JOHN DOUGLAS HOPKINS, OF LONDON, ENGLAND.

Letters Patent No. 97,400, dated November 30, 1869; patented in England, November 20, 1868.

IMPROVED SASH-BALANCE.

The Schedule referred to in these Letters Patent and making part of the same.

To all whom it may concern:

Be it known that I, JOHN DOUGLAS HOPKINS, of London, England, have invented or discovered certain new and useful Improvements in Apparatus for Opening and Closing Window-Sashes; and I do hereby declare that the following is a full, true, and exact description thereof, reference being had to the accompanying drawings, and to the letters and figures marked thereon; that is to say—

The present modes of opening and closing window-sashes are inconvenient, more especially as regards the upper sash.

My invention consists in a device for opening and closing window-sashes, wherein weights are connected to the winding-cord, in order to relieve the drums of the weight of the sashes.

The accompanying drawings represent the manner in which my invention may be carried into effect.

Figure 1 is an elevation, and

Figure 2, a side view of a sash-frame, with a pair of sashes, and having the gearing, or raising and lowering-apparatus, attached to the sill of the sash-frame.

Figure 3 is a plan of the gearing. The arrangement here shown is intended for a pair of sashes of moderate size, glazed with plate-glass.

a is the lower, and *b*, the upper sash.

c c are the suspending-cords of the lower sash.

They pass over pulleys *d*, fixed at the upper part of the sash-frame, and are attached to the sash and to weights *p*, in the usual manner.

They are also attached to the lower end of the weights, and then descend to guide-rollers *e e*, under which they are passed to drum-wheels *f f*, to which their ends are connected.

These drum-wheels *f f* each carry a spur-wheel, *g*, the two wheels *g* gearing into each other, so as to rotate simultaneously, but in opposite directions.

One of the wheels, *g*, is geared into by a pinion, *h*, on a spindle, *l*, formed to receive a winch or cranked handle, *m*.

When it is required to open the lower sash, the handle *m* is applied to the spindle *l*, and then rotated.

The rotary motion is transmitted, by the gearing *h*, to the drum-wheels *f f*, which are thus caused to rotate simultaneously, but in opposite directions, so as to wind up the cords *c c* and raise the sash.

To prevent the sash being moved from the outside, or descending by its own weight when open, I fit a ratchet-wheel, *n*, on the spindle *l*, this wheel being provided with a pawl or catch, *o*, arranged so as to be lifted by the handle *m*, when the latter is applied to the spindle *l*.

The gearing for the upper sash *b* is similar to that

for the lower sash, as just explained, *c c* being the suspending-cords, *f f* the drum-wheels, and *g g* the gearing.

q q are fasteners applied to the lower sash, as shown, in lieu of the fasteners usually applied to the meeting-rails.

Figure 4 represents an arrangement of gearing suitable for a pair of large sashes glazed with plate-glass.

This arrangement differs from that previously described, in the addition of the intermediate wheels and pinions *i i* and *k k*.

Figure 5 represents an arrangement suitable for small sashes glazed with crown-glass or other thin glass.

As less power is required to lift these sashes, the cranked handle is applied directly to the axle of one of the drum-wheels, *f*.

Figures 6 and 7 represent the manner in which my apparatus may be applied to open and close the window-sash in a railway or other carriage-door.

f f are the drum-wheels, geared together by spur-wheels *g g*, as in the arrangement previously described.

One of the spur-wheels, *g*, is provided with a band-wheel, or pulley, *r*, around which a cord, *s*, from another band-wheel, or pulley, *t*, is passed.

On the axle of the band-wheel *t* is a spur-wheel, *u*, geared into by a pinion, *v*.

The drum-wheels *f* are driven by rotating the pinion *v*, by means of a handle, *m*, or otherwise.

In some cases, I dispense with the wheel *u* and pinion *v*, and apply the handle to the axle of the wheel *t*.

The arrangement represented in figs. 6 and 7 may also be applied to windows used in some shop-fronts.

It will be seen that the sashes are balanced, or nearly balanced, whereby there is no strain on the winding-drums, so that the sashes are readily raised and lowered.

I do not claim the gearing, with the cord connected thereto; but

What I do claim, is—

The combination of the balanced sashes *a b*, the winding-cords, and the winding-drums with the weights *p p*, substantially as and for the purpose described.

In witness whereof, I, the said JOHN DOUGLAS HOPKINS, have hereunto set my hand, this 4th day of May, 1869.

J. D. HOPKINS.

Witnesses:

GEORGE HOPKINS,

30 Parliament Street, Westminster.

J. C. NEWBURN,

172 Fleet Street, London.
